DEVICE FOR REMOVING PUTTY FROM WINDOW SASHES

Filed May 3, 1927

Patented Nov. 8, 1927.

1,648,610

UNITED STATES PATENT OFFICE.

ARTHUR J. DWYER, OF AUBURN, NEW YORK.

DEVICE FOR REMOVING PUTTY FROM WINDOW SASHES.

Application filed May 3, 1927. Serial No. 188,570.

This invention relates to an apparatus for removing putty from a window sash and analogous objects.

It is well-known that when putty used in glazing sash, doors and the like becomes set and firmly hardened it adheres closely to the wood so that when it becomes necessary to remove the putty as, for example, by reason of broken glass for replacement with new glass its removal by the usual method is extremely difficult and slow and frequently results in splitting or otherwise mutilating the portions of the wood to which it adheres in addition to irregularities in the removal of the putty and the main object of the present invention is to present a simple apparatus which may be easily and quickly clamped to the sash in such manner that the putty may be removed from end to end of one side by one continuous stroke of a putty-removing tool with which the apparatus is provided thereby avoiding mutilation of the sash and at the same time leaving the edge thereof adjacent the glass smooth and regular for the reception of the replacement glass after the putty along each side of the glass has been removed by similar operations.

In other words, I have sought to provide the clamping device with a guide capable of being adjusted to a position parallel with the line of cleavage for the putty and wood at any one side or edge of the glass and to mount upon the guide a slide carrying a cutting tool which is adapted to register with the line of cleavage so that the movement of the slide along the guide will cause the tool to remove the putty along the line of cleavage in substantially one operation.

Other objects and uses relating to specific parts of the device will be brought out in the following description.

In the drawings:

Figure 1 is a perspective view of a portion of the window sash showing my improved putty removing device operatively mounted thereon.

Figure 2 is an enlarged longitudinal vertical sectional view of the same device, partly broken away, taken on line 2-2, Figure 1, except that the handle of the clamping screw at one end is removed.

Figure 3 is a transverse vertical sectional view taken in the plane of line 3-3, Figure 2.

Figure 4 is an enlarged detail sectional

view of the guide bar and adjacent portion of its supporting bracket together with the clamping screw for holding the guide bar in operative position.

As illustrated, this device comprises a clamping bar —1— having at one end an upstanding bracket —2— and its intermediate portion provided with opposite laterally projecting flat feet —3—, the lower faces of which are disposed in substantially the same plane as the lower edge of the bar —1— to rest upon a suitable supporting table for preventing rocking movement of the bar during the operation of clamping it to the window sash as —A—.

The upper edge of the bar —1— is provided with a series of notches or teeth —4— in longitudinally spaced relation to form a series of stops cooperating with means slideable lengthwise of and upon the bar for holding one of the sash clamping heads presently described in various positions of adjustment.

Similar clamping heads —5— and —5'— are slidably and detachably mounted upon the bar —1— for relative movement toward and from each other and preferably extend upwardly therefrom for engaging opposite rails of the window sash as —A— and firmly holding said sash between them during the putty-removing operation.

For this purpose the lower ends of the heads —5— and —5'— are provided with U-shaped saddles —6— adapted to ride along and upon the upper edge of the bar —1— with their opposite sides engaged with the corresponding sides of the bar to hold the heads in an upright position during their longitudinal movement toward and from each other and also to permit the heads to be removed by upward displacement when desired as, for example, when in storage or transportation.

These brackets are also provided with vertically spaced flanges —7— and —8— projecting inwardly from their adjacent sides toward each other for receiving the adjacent rails of the sash between them, the saddles —6— being secured to the lower ends of the heads —5— by screws —9—, Figure 2.

The upper ends of the heads —5— and —5'— extend equal distances above the upper flanges —8— and also equal distances above the top portions of the saddles —6— and are provided at their upper ends with

similar lengthwise slots —10— parallel with and equal distances from the upper walls of the slots in the lower ends of the saddles —6— for receiving and supporting a guide bar —11—, the slots —10— being preferably open at the top to permit the removal of said guide bar by upward displacement.

The upper flanges —8— are somewhat shorter laterally than the lower flanges —7— so as to permit the sash to be placed first upon the lower flanges just preceding the tightening of the clamping heads upon the sash.

These clamping heads —5— and —5'— may be moved by hand lengthwise of and upon the bar —1— to bring them into clamping engagement with opposite sides of the sash —A— and when properly positioned for tightening the clamping head —5'— will be held against outward movement by a follower block —12— which extends around the four sides of the rectangular bar —1— and is also slidable by hand lengthwise of and upon the same.

A pawl —13— is pivoted at —14— to the follower —12— to engage any one of the notches —4— and is yieldingly held in its holding position by means of a coiled spring —15— carried by the block —12— just above the pivot —14— as shown in Figure 2, said pawl being provided with a handle —13'— by which it may be released against the action of the spring.

An additional follower or block —16— extends around the four sides of the rectangular bar —1— and is slidable lengthwise of and upon said bar by means of a screw —17— for adjusting the clamping head —5— toward and from the opposite clamping head —5'— as the screw is rotated in one direction and for withdrawing the follower —16— from the clamping head —5— as the screw is rotated in the opposite direction to permit the clamping head —5— to be moved away from the clamping head —5'—.

The inner end of the screw —16— is journaled in an opening in the upper end of the follower —16— and is held against axial movement by means of a screw —18— engaging in an annular groove —19— in the adjacent portion of the screw shaft as shown in Figure 2.

The intermediate portion of the screw is engaged in a threaded aperture in the upper end of the bracket —2— which is secured to the adjacent end of the bar —1— by means of a set screw or bolt —21—, the outer end of said screw being provided with a hand crank —20— by which it may be rotated.

The guide bar —11— is seated in the slots —10— in the upper ends of the clamping heads —5— and —5'— parallel with the clamping bar —1— and axis of the screw —17— and also parallel with the horizontal

plane of the ledges —7— and —8— to extend approximately the full length of the bar —1—.

Suitable means is provided for clamping and releasing the bar —11— in and upon the upper ends of the clamping members —5—, said means consisting, in this instance, of clamping screws —21— which are engaged in threaded apertures in one of the walls of the adjacent slots —10— as shown in Figure 4.

A tool carriage —22— is slidable by hand lengthwise of and upon the intermediate portion of the guide bar —11— between the upper ends of the clamping members —5— and —5'— and for this purpose is provided with oppositely projecting handles —23—.

This carriage is provided with a vertical guide opening —24— at right angles to the bar —11— for receiving a vertically adjustable tool holder —25— carrying at its lower end a knife blade —26— for removing the putty as —a— of the sash —A— at its plane of cleavage with the sash.

The opening —24— and portion of the tool holder —25— movable therein are preferably rectangular in cross section to hold the tool —26— in a plane parallel with the guide bar —11—.

The upper end of the tool holder —25— is provided with a reduced cylindrical threaded extension —27— projecting some distance above the upper face of the carriage —22— and engaged by a hand nut —28— having its lower end provided with an annular flange —29— which engages in a groove —30— in the adjacent portion of an upward extension —31— of the carriage —22— as shown in Figure 3 for holding the nut against axial movement and thus permitting the tool holder —25— with the tool thereon to be operatively adjusted vertically by rotation of the nut —28— in one direction or the other.

Operation.

When it is desired to remove the putty from any one side of the sash —A— the clamping bar —1— will be placed in operative position upon a suitable supporting bench or table with its feet —3— resting thereon to hold the bar against turning movement after which the followers —16— and clamping members —5— and —5'— will be drawn outwardly away from each other a sufficient distance to allow the sash to be placed between said clamping members —5— and —5'— and upon the lower ledges —7— with the line of cleavage between the putty to be removed and the adjacent portion of the sash in exact alinement with the lower edge of the cutter —26—.

This alinement can be accurately determined by first moving the cutter to one side of the sash and registering it with the line

of cleavage of the adjacent portion of the putty and then moving the cutter to the opposite side of the sash to register it with the line of cleavage of that portion of the putty after which the sash may be tightly clamped by the adjustment of the followers —12— and —16— and screw —17— to firmly hold it between the clamping members —5— and —5'—, it being understood that the guide bar —11— is then tightly clamped to the upper ends of the members —5— and —5'—.

As soon as the sash is properly adjusted and tightened between the clamping members —5— and —5'— the tool holder —25— will be adjusted by means of the nut —28— to cause the cutting edge of the knife —26— to enter between the putty and adjacent portion of the sash frame to approximately the plane of the glass as —A'— whereupon the carriage —22— will be moved the entire length of the putty to be removed by means of the handles —23— thereby shearing the putty from the frame and at the same time assuring a smooth cut parallel with the adjacent rail of the sash.

This movement of the carriage —22— along the bar —11— may be repeated if necessary but usually one movement from end to end of the sash rail will be sufficient to remove the entire line of putty.

The apparatus shown and described is particularly simple and affords an expeditious means for removing the putty without mutilating the sash rails but it is evident various changes may be made in the details without departing from the spirit of this invention.

What I claim is:—

1. A device for removing putty from window sash and the like comprising a guide adapted to extend along this putty line, means for holding the guide in fixed relation to the sash and a tool holder movable along the guide and provided with a putty-removing tool.

2. In a device for removing putty from window sash and the like comprising a sash clamp and a guide bar thereon, said clamp being adjustable on the sash to bring the guide bar into parallel relation with the plane of contact of the putty with the sash and a tool-holder slidable along the bar and provided with a putty removing tool movable in said plane.

3. A device for removing putty from win-

dow sash and the like comprising a clamping bar, clamping heads relatively adjustable along and upon the clamping bar for engaging opposite sides of a sash, means for holding said heads in their adjusted positions, a 60 guide bar mounted on said heads, a carriage slidable along and upon the guide bar and a tool-holder mounted on the carriage and provided with a putty removing tool.

4. A device for removing putty from window sash and the like comprising a guide bar, means for supporting the guide bar along the line of putty to be removed, a carriage slidable along and upon the guide bar, a tool-holder mounted on the carriage and 70 provided with a putty-removing tool, and means for adjusting the tool-holder transversely of the bar.

5. A device for removing putty from window sash and the like comprising a clamping bar, clamping heads slidable lengthwise of and upon the bar, means including a clamping screw for adjusting one of the heads lengthwise of the bar toward the other head, means for holding the last-named head in 80 different positions of adjustment against movement in the direction of movement of the first-named head by the screw, a guide bar mounted on the heads parallel with the clamping bar, a carriage slidable lengthwise of and upon the guide bar, a tool-holder mounted on the carriage and provided with a putty-removing tool, and means for adjusting the tool-holder transversely of the guide bar.

6. A device for removing putty from window sash and the like comprising a clamping bar, clamping heads adjustable lengthwise of and upon the bar, followers movable lengthwise of and upon the bar independently of the clamping heads, means for holding one of the followers against endwise movement in one direction relatively to the clamping bar, means for adjusting the other follower in reverse directions, a guide bar 100 mounted on the clamping heads parallel with the clamping bar, a carriage slidable lengthwise of and upon the guide bar, a tool-holder mounted on the carriage and provided with a putty-removing tool, and means for adjusting the tool-holder transversely of the guide bar.

In witness whereof I have hereunto set my hand this 29th day of April 1927.

ARTHUR J. DWYER.
